UNITED STATES PATENT OFFICE.

REASON C. THARP AND PEARLEY G. BUCKLES, OF OSCEOLA, MISSOURI.

AIR-PRESSURE-PRODUCING ATTACHMENT FOR GASOLENE-TANKS.

1,245,165.

Specification of Letters Patent.

Patented Nov. 6, 1917.

Application filed February 15, 1917. Serial No. 148,874.

To all whom it may concern:

Be it known that we, REASON C. THARP and PEARLEY G. BUCKLES, citizens of the United States of America, residing at Osceola, in the county of St. Clair and State of Missouri, have invented certain new and useful Improvements in Air-Pressure-Producing Attachments for Gasolene-Tanks, of which the following is a specification, reference being had therein to the accompanying drawing.

This invention relates to an air pressure producing attachment for liquid containing tanks, particularly gasoline tanks, whereby suitable pressure may be produced within the tank to force the gasoline or other contents thereof from the tank to a desired point.

The primary object of the invention is to provide a device of this character by means of which air under pressure may be forced into the gasoline supply tank of an automobile or the like, in which the gasoline is fed by gravity from the tank to a carburetor, so that when the gasoline in the tank reaches a low level and the machine is climbing a grade the gasoline may be forced by air under pressure from the tank to the carburetor to overcome well known defects occurring under such conditions of service.

A further object of the invention is to provide an attachment of the character described whereby air may be supplied to the tank from a hand pump forming part of such attachment, or from an auxiliary source of compressed air supply, and whereby the pressure from the tank may be readily and conveniently released when desired.

A still further object of the invention is to provide a pressure producing attachment of the character set forth which may, if desired, be applied to the plug or closure sealing the filling inlet of the tank, thus providing for the ready and convenient removal of the parts of the attachment for cleaning, repairs or other purposes without the necessity of employing auxiliary parts.

The invention consists of the features of construction, combination and arrangement of parts hereinafter fully described and

claimed, reference being had to the accompanying drawing, in which:—

Figure 1 is a top plan view of a cap or closure plug embodying the improved features of our invention.

Fig. 2 is a view, partly in section and partly in side elevation, of the device as applied for use to a gasoline tank.

Fig. 3 is a longitudinal section through the combined filling and escape valve.

Fig. 4 is a view of the plug thereof.

Fig. 5 is a sectional view through the auxiliary charging valve.

In the present embodiment, we have shown the application of our invention to the threaded closure plug 1 of the threaded filling inlet 2 of a gasoline tank 3, a portion of which is disclosed, and which may be of any of the types commonly employed upon automobiles. This plug or cap is provided with a rim flange 4 to clamp a sealing disk 5 against the wall of the opening 2 to closely seal the joint, and said cap is provided with gripping lugs or projections 6 for convenience in applying and removing it, as will be readily understood.

A portion of the body of the plug or cap is provided with an opening 7 for passage of a pump tube or casing 8, which is brazed, soldered or otherwise rigidly fitted therein. This pump has its piston or plunger 9 connected with a stem 10 projecting outwardly through the top of the pump casing and provided with a suitable handle 11, whereby the piston may be reciprocated for charging purposes in the usual way. The lower end of the pump casing extends downwardly into the tank to a suitable point in proximity to the bottom of the tank and is provided with a check valved charge outlet 12, the check valve employed being preferably of the type commonly used in the inlet tubes of pneumatic tires, although it may be of any other suitable construction.

It will be understood from the foregoing description that the operator, whenever desired, may charge the tank with air to a desired pressure above the level of the gasoline, so that the gasoline will be forced from the tank to the carburetor, no matter what

the respective levels of the tank and carbureter may be. Thus in an automobile equipped with a gravity feed system pressure may be supplied to the tank when the 5 level of the gasoline is below the level of the carburetor, as when the gasoline is at a low level and the vehicle is climbing a grade, so that an efficient feed of the gasoline to the carburetor may be established.

10 For the purpose of venting the pressure from the tank when not needed or desirable, I provide a vent valve which may also be employed as a charging device. This valve, generally denoted by 13 comprises a casing 14 threaded at its lower end into the cap and having a longitudinal passage 15 and a transverse tapered passage 16. Intersecting the tapered passage 16 at its enlarged end is a venting groove or recess 17. Fitted with- 15 in the recess 16 is a valve plug 18 having a transverse passage 19 for coöperation with the passage 15 and also having a longitudinal groove or recess 20 adapted to connect the lower portion of the passage 15 with the 20 recess 17 when the valved plug 18 is in a prescribed position. The plug 18 is pro- 25 vided with a finger piece 21 at one end and a stem 22 at its opposite end. On the stem 22 are spaced washers 23 and 24, the washer 23 bearing against the adjacent side of the 30 casing and a coiled spring 24 being inter- 35 posed about said stem between said washers to hold the valve snugly seated and take up wear. A cotter pin or key 25 is provided for holding the washers and spring in position.

In the use of the pump 8, the valve plug 18 is closed against the escape of air through the vent recesses, so that the tank may be charged with air through the pump in an 40 obvious manner, but this pressure may be released whenever desired by turning the valve plug 18 to the position shown in Fig. 3, whereupon the pressure will vent through the recesses. The valve plug may be al- 45 lowed to remain in the normal position shown in Fig. 3, so that the recesses 17 and 20 will serve the additional functions of an air inlet, to allow air to enter the tank normally to take the place of the gasoline 50 discharged. Connected with the upper end of the passage 15 is a check valved filling inlet 26, which may be of the type hereinbefore referred to, and which adapts the valve 13 to be employed as a charging device, for 55 the admission of air through an auxiliary hand pump in the event that the pump 8 should become inoperative from any cause. It will thus be seen that the valve 13 serves a plurality of functions and provides a 60 valuable feature in a device of this character.

If desired, we may also provide the cap or plug with a check valved charging device or tube 27, which may be employed in the

event of possible inoperativeness of the other charging devices, or for charging the 65 tank from a charging station in which the air is taken from a compressed air tank or reservoir. The construction of this charging device 27 will be readily understood by reference to Fig. 5, from which it will 70 be seen that said charging device corresponds generally in construction to the check valved charging or filling tubes of pneumatic tires commonly employed.

While the features of construction may 75 be mounted separately upon the tank, we prefer to mount the same, as shown, upon the closure cap or plug 1, as this obviates the necessity of drilling auxiliary openings in the tank, and at the same time provides 80 for the ready removal of the parts of the charging device with the cap or plug for convenience in cleaning, repairing, replacing worn parts and otherwise maintaining the same in proper working condition. 85

Having described our invention, we claim:

1. In a device of the character described, the combination of a gasoline tank having a filling inlet, a detachable cap for closing said inlet, a check valved air inlet tube carried by the cap, means for forcing air into the tank through said check valved air inlet tube, an air outlet tube mounted on the cap separate from and independent of communication with said air inlet, and a valve 90 controlling said air outlet tube. 95

2. In a device of the character described, the combination of a gasoline tank having a filling inlet, a cap for closing said inlet, an air pump carried by the cap, a check 100 valved inlet tube carried by the cap, a second tube carried by the cap and having a check valved inlet and an outlet, and a plug carried by said second tube and controlling both the inlet and the outlet. 105

3. In a device of the character described, the combination of a gasoline tank having a filling inlet, a cap for closing said inlet, a pump carried by the cap for supplying air to the tank, a casing carried by the cap and having air inlet and exhaust passages for supplying air to and discharging the same from the tank, and a single plug mounted upon said casing and having passages and recesses for respectively controlling the 110 115 aforesaid passages.

4. A device of the character described embodying a tank, a valve casing having a longitudinal passage and a transverse passage, and having a recess intersecting said transverse passage, a check valve communicating with the upper end of the longitudinal passage, and a transverse rotary valve plug fitting in said transverse passage and having a transverse passage for coöperation 120 125 with the longitudinal passage of the casing

and a longitudinal recess at an angle to said passage for coöperation with the recess of the casing and the aforesaid plug recess intersecting said casing longitudinal passage.

5. In a device of the character described, the combination of a gasoline tank having a filling inlet, a plug or cap for closing said inlet, an air pump carried by said cap, a valve casing carried by the cap and having

10 passages for the inlet and exhaust of air,

a check valve controlling the inlet passage, and a plug controlling both of said passages.

In testimony whereof we hereunto affix our signatures in the presence of two witnesses.
